TREATING LUBRICATING OIL FRACTIONS

Cary R. Wagner, Chicago, Ill., assignor, by direct
and mesne assignments, of one-half to The Pure
Oil Company, a corporation of Ohio

Application December 17, 1930, Serial No. 502,951

3 Claims. (Cl. 196—18)

This invention relates to an improved process for treating lubricating oil fractions obtained from the distillation of crude petroleum oils for the purpose of removing undesirable wax compounds therefrom, and the process has particular reference to the employment of certain improved solvents which have low solubility for amorphous wax and when admixed with the lubricating oil distillate, permits the latter to be forced through a filter press without necessitating a preheating of the distillate to a cracking temperature to produce a crystalline wax, or what is known as a pressable distillate.

If a cracking operation is resorted to, it destroys or reduces the viscosity of the heavy lubricating fractions at the same time the cracking operation changes the physical properties of the wax from an amorphous to a crystalline form in producing a pressable distillate. Therefore, such a treating process which involves any appreciable cracking of the lubricating oil stock results in the loss of a most valuable portion of the total potential lubricants in the crude oil from which the initial distillation is effected. With the present invention, however, by the employment of certain selected solvents, the crystalline form of the wax is no longer an important factor, and I am enabled to separate, through simple distillation, the lubricating oil fractions from the crude and to then, by the mere addition of my selected solvents, pass the subsequently chilled lubricating oil fractions directly through a filter press to remove the undesired wax compounds from the lubricating oil fractions at desired temperatures.

In accordance with the present invention, a solvent is selected which possesses the unique property of dissolving both oil and wax in large quantities at temperatures varying around 100° F., but which with decreasing temperatures shows a rapid decrease in its solvent powers for wax and with only a slight change in its solvent powers for oils. Among certain others, the solvents which I have found to be very effective in carrying out this process are: methyl ethyl ketone, n-butyl alcohol, isobutyl alcohol, isopropyl alcohol, and also mixtures of the solvents in varying proportions with light petroleum naphthas, may be used effectively in the following described process of dewaxing.

The following chart shows the relative solvent properties of two of the solvents as compared with the regular petroleum naphtha.

Temperature of test	Per cent. of wax soluble in solvent		
	Methyl ethyl ketone	N-butyl alcohol	Naphtha
0° F.	0.002	0.005	0.42
20° F.	0.007	0.02	1.40
30° F.	0.012	0.03	2.40
40° F.	0.022	0.04	3.90
50° F.	0.042	0.07	6.60
60° F.	0.084	0.14	11.00

In order to produce a lubricating oil with a pour test of 10° F., it is necessary, in the operation of previous methods, to refrigerate to —10° F., or lower, when using naphtha as a solvent in the process of dewaxing. With the use of the above solvents, I have found that it is usually sufficient to cool to the temperature of the desired pour point of the oil or 5° F. lower. Therefore, by my present method, the costs of refrigeration are lower and coincidentally the capacity of the filter presses employed is increased. These factors from an economic standpoint are of considerable importance.

For a further understanding of the invention, reference is to be had to the accompanying drawing, wherein the single figure illustrates diagrammatically apparatus used in carrying out the present invention, and the figure also partakes somewhat of the nature of a flow chart.

The crude oil may be distilled in any conventional manner although, of course, care should be taken that cracking does not occur to any appreciable extent as this will tend to destroy or lower the lubricating value of the distillate. The distillate from about 60 viscosity Saybolt Universal at 100° F. to the end of the distillation is cut into a tank by itself, or if good enough fractionating equipment is present, a distillate of the desired viscosity, flash and fire tests may be produced directly. In the first case this crude distillate is re-run in a second still taking off distillate until the residue or bottoms in the still have the desired flash, fire and viscosity properties. In most instances, it is satisfactory to produce a distillate of the same viscosity as the finished neutral oil desired, since removal

of the wax and treatment of the dewaxed oil usually just about offset each other in their total effect upon viscosity. The process that I shall describe in detail hereinafter will be one 5 wherein a fractionating tower is used to remove light fractions from a crude distillate containing both wax distillate and what is known as slop wax distillate.

Referring more particularly to the drawing, 10 the crude distillate from the tank A is pumped through a pipe line 1 into a suitable type of distillation still B, wherein the oil is raised to the desired temperature necessary to effect the vaporization and subsequent separation of the low 15 boiling compounds present in the distillate or other charging stock. Care should be taken however in the operation of the still B to avoid overheating or cracking of the oils charged thereto. The oils after being heated in the still B pass 20 through an outlet line 2 into any efficient form of a fractionating tower, the latter being indicated by the reference character C. In this fractionating tower there takes place a sharp separation of the low boiling products such as gasoline, 25 kerosene and gas oil, the said low boiling products leaving the top of the tower through the outlet line 3. Line 3 may lead to suitable condensers, not shown, wherein the low boiling products may be fractionally condensed, separated and collected. 30

The construction and operation of the tower C is such that the heavier fractions, which comprise the distillate containing the desired neutral lubricating oil, together with paraffin wax, petro- 35 latum and other incidental impurities, such as asphaltic bodies, resins, and the like, are discharged from the lower portion of the fractionating tower by way of a pipe line 4. Leading into the line 4 is a valve controlled pipe line E', which 40 extends from a solvent tank E. This tank may contain any one of the above identified or other equivalent selected solvents and the distillate passing through the line 4 is mixed with a suitable quantity of this solvent in proportions de- 45 pending upon the viscosity and wax content of the oil. Usually these proportions are not less than an equal quantity nor more than five times the volume of the distillate under treatment. For example, I may say 75% of the special solvent to 50 approximately 25% of the lubricating oil distillate. It will be appreciated however that this example is given merely as one of many and that I am not limited to the numeral ratio set forth thereby.

55 The distillate is forced through the line 4 wherein it is mixed with the solvent as above described and is forced through a wax chilling apparatus, indicated at D. The distillate-solvent mixture upon entering the wax chillers may possess a temperature of approximately 90° F. This wax chilling apparatus may be of any conventional type such as are commonly used in oil refineries. It may also be of a tank type with brine coolers and agitators instead of the closed 65 coil type disclosed in the drawing. After the distillate is cooled in the wax chillers to the desired pour test, the cooled mixture is then pumped under pressure through a pipe line 5 into a standard filter press, in which the wax is retained upon the filter plates F allowing the dewaxed oil to drop downwardly into the pan or receiver G. From this receiver, the dewaxed oil is transferred by means of the pipe line G' to a working tank W.

75 The dewaxed oil passes from the tank W

through a line 6 to a recovery still indicated at H. In this recovery still, ample temperatures are maintained so that the solvent is distilled over through the line 7 into a condenser I, from which the solvent passes through the line 8 and thence back to the tank E for re-use in the system. Owing to the fact that these solvents are miscible with water, it is preferred not to use a steam distillation in recovering the solvent.

In order to overcome excessively high temperatures in the recovery still, a small amount of neutral gas or refinery residue gas is introduced through a pipe line 10 into a perforated coil disposed in the bottom of the still H towards the end of a given distilling operation. This gas acts substantially like steam in reducing the temperature required to secure complete distillation of the solvent and yet avoids the presence of water in the recovered solvent. Before pumping out the still H, however, at the end of a distillation period, it is desirable to pass steam through the oil for a few minutes to purge it of dissolved gas. This steam may enter the still H through the pipe line 11 and may find exit through the line 12.

The dewaxed oil in the still H now has the desired flash, fire and pour characteristics but, on the other hand, may possess a bad color and other impurities. Therefore, to correct this situation, the distillate is withdrawn from the still H by way of a pipe line 9 into a cooler J and thence through a line 13 into an acid treating agitator K. The oil in the agitator K is mixed with concentrated sulphuric acid at a temperature between 75° to 80° F. After being agitated in the unit K, 35 the oil-acid mixture is passed through a line 14 into a settling tank L. The acid sludge formed by the operation in K is withdrawn from tank L through an outlet line 15 and suitably removed from the system. The acid treated oil is withdrawn from the tank L through a line 16 and enters a caustic agitator M, in which the oil is neutralized with caustic soda and is discharged from the agitator M through a line 17 and enters a settling tank N. The caustic sludge is withdrawn from the settling tank N and is discharged from the process through a line 18. The neutralized oil is then withdrawn through a pipe line 19 and enters the filter O containing fuller's earth or its equivalent. The filtered oil leaves the filter O and passes by way of a line 20 to a suitable storage tank as a finished neutral lubricating oil.

In view of the foregoing, it will be seen that the present invention provides a method of treating lubricating oil fractions of crude oil which particularly avoids any step or operation tending to detract from the ultimate value of the end product as a lubricating oil. Especially, the process overcomes the necessity for overheating or cracking the oil during its initial distillation for the purpose of producing a solvent containing pressable distillate having a crystalline wax content. While the physical equipment employed by the present invention is somewhat similar to that now in general use, yet there are marked differences which are of considerable importance. For example, in the operation of the initial distillation still, such as the one indicated at B, the heated oils do not attain a cracking temperature as has usually been the practice to produce a pressable distillate and second, so far as I am aware, it is novel to produce a pressable distillate containing the selected solvents above identified. The present invention also enables the chillers D when operating to produce a lu- 75

bricating oil of a certain pour point to operate at a higher temperature than has been customary heretofore and also increases the capacity of the filters F in the matter of producing de-waxed oils. The particular importance of these operations will be appreciated by those skilled in the art.

In the ordinary processes heretofore employed, it is not possible to filter-press wax distillate unless the wax has been cracked to produce what is known as a crystalline wax or, as it is sometimes termed, pressable distillate. This cracking operation destroys or minimizes, as above explained, the viscosity of the heavy lubricating fractions at the same time that it produces the crystalline form of the wax and loses a most valuable portion of the total potential lubricants in the crude. With my present method, I am not concerned as to the crystalline form of the wax, and since no cracking of the oil has taken place in the preparation of the distillate, I have lost none of its most viscous products. The difference in the yield of lubricants from crude oil may be readily seen when it is noted that in one grade of light Pennsylvania crude, by conventional methods, there was made 6.0% of 150 viscosity neutral oil, while the present method yielded 9.0 to 10.0% of the same viscosity neutral oil. In heavier oils the differences are still more in favor of the process comprising the present invention.

What is claimed is:

1. The process of producing lubricating oil from an uncracked wax distillate which comprises mixing said uncracked distillate having a boiling point above that of gas oil with a solvent liquid containing sufficient methyl ethyl ketone

so that at temperatures of approximately 100° F. the solvent liquid has substantially complete solvent action on said distillate and at a temperature of 0° F. has substantially no solvent action on the wax-containing bodies therein and upon removal of said wax-containing bodies and solvent the said distillate has a cold pour point substantially the same as the temperature of refrigeration to which the distillate is subjected for wax removal, refrigerating the mixture to a temperature substantially similar to the low pour point desired in the final product to form a pressable wax mixture, pumping said mixture under pressure into a filter press, separating the wax from diluted oil, in the absence of extraneous cellular filter aid material, by means of said filter press, and separating the solvent liquid from the separated oil solution.

2. The method of dewaxing uncracked petroleum wax distillate within the lubricating oil range which comprises completely dissolving said distillate in methyl ethyl ketone, chilling the solution to a temperature sufficient to solidify the wax present in said distillate and to form a filterable wax mixture, introducing the filterable wax mixture under pressure into a filter press, separating the wax from the diluted oil by filtration in the absence of extraneous cellular filter aid material, and separating the methyl ethyl ketone from the dissolved liquid hydrocarbons.

3. The method of claim 2 wherein at least one volume of methyl ethyl ketone, but not more than five volumes of methyl ethyl ketone, is mixed with each volume of wax distillate during the process of dewaxing.
